W. M. DUNCAN.

CHAIN GRATE.

APPLICATION FILED NOV. 23, 1917. RENEWED JUNE 21, 1920.

1,365,669.

Patented Jan. 18, 1921.

UNITED STATES PATENT OFFICE.

WILLIAM M. DUNCAN, OF ALTON, ILLINOIS.

CHAIN GRATE.

1,365,669.

Specification of Letters Patent. Patented Jan. 18, 1921.

Application filed November 23, 1917, Serial No. 203,533. Renewed June 21, 1920. Serial No. 390,668.

To all whom it may concern:

Be it known that I, WILLIAM M. DUNCAN, a citizen of the United States of America, a resident of Alton, in the county of Madison, 5 State of Illinois, have invented certain new and useful Improvements in Chain Grates, of which the following is a full, clear, and exact description, reference being had to the accompanying drawing, forming a part of 10 this specification.

My invention relates to improvements in chain grates, the main object being to produce a grate of this kind having its links so constructed that the draft between the 15 chains will flow transversely of the fuel supporting elements, instead of being permitted to flow longitudinally of the grate structure. Prior to this invention, chain grates have been made of endless rows of grate links, 20 loosely connected together to permit the draft to pass through the grate structure. The object is to force the draft transversely of the chains, to or from the fuel supported thereon. However, in the earlier structures, 25 the air currents between the loosely connected grate links can flow longitudinally of the grate, and escape through a course of low resistance, instead of passing through the bed of fuel at points where the draft is 30 needed. In some chain grate structures it is desirable to provide a strong draft near the point at which fuel is delivered to the grate, and to weaken or dispense with the draft near the rear end of the structure 35 where the ashes are discharged from the grate. I have manufactured many chain grates having different draft zones and provided with independent dampers for the purpose of regulating the draft at the different zones. Theoretically, this is most desirable, but in actual practice the highest 40 efficiency cannot be obtained if the draft is permitted to pass longitudinally of the grate, from one zone to another.

According to the present invention, the 45 grate links are provided with baffles for obstructing the air currents tending to flow longitudinally of the grate structure. The baffle extending from a side of a grate link, 50 preferably lies between the ends of two links in an adjacent row, so as to prevent the air currents from flowing longitudinally of the rows of links.

Figure I is a longitudinal section of a

chain grate constructed in accordance with 55 the present invention.

Fig. II is an enlarged fragmentary plan view, showing a number of grate links and the pivot rods connecting said links, the end portions of two links being broken away to 60 show one of the baffle members which lies directly below said end portions.

Fig. III is a side elevation of the parts shown in Fig. II.

Fig. IV is a transverse section taken approximately on the line IV—IV, Fig. III.

Fig. V is a perspective view of one of the grate links.

To illustrate the invention I have shown a supporting frame 1 provided with a hopper 2 for the discharge of fuel to a chain grate A. The grate structure comprises many endless rows of grate links A', and pivot rods 3 connecting said grate links. The endless chains produced by connecting 75 the grate links, are fitted to toothed drive wheels 4 fixed to a power shaft 5 near one end of the supporting frame, and also fitted to idle wheels 6 near the opposite end of said frame. The links at the upper portion 80 of the grate structure travel over rollers 7, while the lower links travel over rollers 8. The power shaft 5 may be operated in any suitable manner.

9 designates draft boxes, surrounded by 85 the endless chains, said draft boxes being open at the top for the discharge of air to the fuel supporting elements. Some of the rollers 7 are combined with flanged members 10 or 10' to form ash-seals at the upper 90 edges of the draft boxes. The ashes accumulating between rollers 7 and the flanged members 10 or 10', prevent the draft from escaping between the upper edges of the draft boxes 9 and the bottom faces of 95 the adjacent grate links. Dampers 12, arranged in the draft boxes 9, can be regulated independently of each other to control the draft at different points in the bed of fuel. A relatively strong draft should usually be 100 maintained near the front end of the structure where the fuel is delivered to the grate, but the draft can usually be entirely dispensed with near the rear end of the grate, where the ashes are discharged therefrom. 105 To obtain the highest efficiency, the dampers 12 can be adjusted to control the draft at various different points in the grate struc-

ture. Obviously, the desired results could not be obtained if the air currents between the rows of links are permitted to flow longitudinally of said rows of links. The 5 air passing from the top of the draft box should flow vertically between the rows of links, and to accomplish this it is necessary to prevent the air from flowing longitudinally of the links.

10 In the preferred form of the invention, the grate links A' are provided with baffles B in the form of ribs, as shown most clearly in Fig. V. Each grate link is also provided, near its ends, with pivot receiving openings 15 3' (Fig. V) and the baffle rib B is formed on one side of the link, approximately midway between said openings. It is important to observe that the links of the adjacent chains are staggered relative to each other, 20 so that the ends of any given link are not in alinement with the ends of the links on opposite sides thereof. The baffle rib B, extending from one of the interposed links, lies between end portions of two links of the 25 next adjacent chain. The upper end portions of each link are extended as shown at 13 (Figs. III and V) and these extended end portions lie directly above a baffle rib B. In other words, the baffle ribs of one 30 chain overlap and lie between the ends of the links of an adjacent chain. In the structure shown, the baffle ribs B are approximately as wide as the link from which they extend, and each baffle rib therefore extends 35 across the links which it overlaps, as shown most clearly in Figs. II and IV.

By forming the links with baffle ribs B as herein disclosed, I provide a multitude of baffles, each extending from one link and 40 overlapping the ends of adjacent links, so as to very effectively impede the air currents tending to flow longitudinally of the grate. As a result, the draft can be directed to any 45 particular point on the bed of fuel, and the air currents are prevented from taking a course of low resistance by flowing through the thin bed of ashes near the rear end of the grate.

In moving around the wheels 4 and 6, 50 the grate links turn on their pivots 3, and clinkers, or the like, will sometimes drop between the separated ends of the links passing around the wheels 6. Thereafter, when the separated ends move toward each other, 55 the clinkers, or the like, will be crushed at the upper ends of the baffle ribs B. The upper end of each baffle rib is enlarged, and the top face of this enlarged portion is recessed to form a pocket 14 for the crushed 60 material resulting from the crushing of clinkers or the like.

I claim:—

1. A chain grate comprising rows of grate links, the links of one row being provided 65 with baffles which overlap the links of the

next adjacent row, said baffles extending vertically at the lower portions of the links when the links are in fuel-supporting positions to impede the air currents tending to flow longitudinally of the grate. 70

2. A chain grate comprising rows of grate links, the links of one row being provided with baffles which overlap the links of the next adjacent row to impede the air currents tending to flow longitudinally of the 75 grate, said baffles being in the form of ribs extending laterally from the sides of the grate links at their lower portions when the links are in fuel-supporting positions.

3. A chain grate comprising rows of grate 80 links, the links of one row being provided with baffles leading into proximity to the lower edges of the links and which extend between the links of the next adjacent row.

4. A chain grate comprising endless rows 85 of grate links, the links of adjacent rows being staggered relative to each other, so that the ends of the links in an interposed row are not in alinement with the links at opposite sides thereof, said interposed links 90 being provided with baffles which extend between the ends of the links in an adjacent row, so as to impede the air currents tending to flow longitudinally of the grate, each of said baffles comprising a rib formed 95 on one side of a grate link and extending from near the lower edge of the link to a point near the top of said link.

5. A chain grate comprising endless rows 100 of grate links, the links of adjacent rows being staggered relative to each other, so that the ends of the links in an interposed row are not in alinement with the links at opposite sides thereof, said interposed links 105 being provided with baffle ribs which extend between end portions of the links in an adjacent row, so as to impede the air currents tending to flow longitudinally of the grate, and the upper end portions of the links being extended so as to overlie said 110 baffle ribs.

6. A chain grate comprising endless rows 115 of grate links, the links of adjacent rows being staggered relative to each other, so that the ends of the links in an interposed row are not in alinement with the links at opposite sides thereof, draft boxes surrounded by said endless rows of grate links, 120 said draft boxes being open at the top for the discharge of air currents transversely of the upper portion of the grate, and means for controlling the flow of air through said draft boxes so as to control the draft at different parts of the grate, said interposed links being provided with baffles which extend 125 between the end of the links in an adjacent row and into proximity to the lower edges of the links, so as to impede the air currents tending to flow longitudinally of the grate. 130

7. A grate link having pivot receiving openings near its ends, and a baffle approximately midway between said openings, said baffle being in the form of a rib extending laterally from one side of the link and into proximity to the lower edge of the link.

8. A grate link of the character described having pivot receiving openings near its ends, and a baffle rib extending from the lower edge of the link to a point near the upper edge thereof, said baffle rib being formed on one side of the grate link approximately midway between said openings, and the upper end portions of the link being extended for the purpose described.

9. A grate link of the character described having pivot receiving openings near its ends, and a baffle rib extending from the lower edge of the link to a point near the upper edge thereof, the top face of said baffle rib being recessed to form a pocket, said baffle rib being formed on one side of the grate link approximately midway between said openings, and the upper end portions of the link being extended for the purpose described. 20

In testimony that I claim the foregoing I hereunto affix my signature.

WILLIAM M. DUNCAN.
